UNITED STATES PATENT OFFICE.

FREDRICK R. TUCKER, OF LAFAYETTE, ALABAMA.

HEADBOARD FOR GRAVES.

1,372,575.

Specification of Letters Patent. Patented Mar. 22, 1921.

Application filed August 13, 1920. Serial No. 403,182.

To all whom it may concern:

Be it known that I, FREDRICK R. TUCKER, a citizen of the United States, residing at Lafayette, in the county of Chambers and

5 State of Alabama, have invented certain new and useful Improvements in Headboards for Graves; and I do hereby declare the following to be a full, clear, and exact description of the invention, such as will enable others 10 skilled in the art to which it appertains to make and use the same.

This invention has relation to certain new and useful improvements in a head board for a grave and has for its primary object 15 the provision of a head board which will be of improved construction and comparatively inexpensive and in which the metallic letters may be readily arranged and secured in sockets formed therefor in the head board 20 front plate carried by the supporting post which may be readily driven into the ground.

The invention has for another object the provision of a head board for a grave of 25 the character stated which will be constructed and arranged so that the letters may be readily placed in the rows of sockets formed therefor and securely held against turning movement or displacement by the fastening 30 means employed for fastening the letters in position.

With the foregoing and other objects in view as will appear as the description proceeds, the invention consists in the novel 35 construction, combination and arrangement of coöperating elements as hereinafter more specifically set forth, claimed and shown in the accompanying drawings, in which:

Figure 1 is a front elevation of the improved form of head board for a grave.

Fig. 2 is a vertical section through the same, taken on the plane of line 2—2 of Fig. 1.

Fig. 3 is a detail transverse section on the plane of line 3—3 of Fig. 1.

Fig. 4 is a detail view of one of the characters removed from the front board or plate, showing the front face of the character and the block upon which it is carried.

50 Fig. 5 is a detail view of the character removed, showing the rear side thereof and the threaded shank extended therefrom.

Fig. 6 is a fragmentary detail view of the front plate, showing one of the sockets 55 formed therein to receive a removable character as illustrated in Figs. 4 and 5.

Fig. 7 is a fragmentary detail section through one of the character carrying blocks and the front plate, as taken on the plane of line 7—7 of Fig. 1.

Referring more in detail to the drawings in which similar reference characters designate corresponding parts throughout the several views, 1 indicates the front plate which may be formed of metal or any other suitable material and which has a lower central extension 2 having a perforation 3 therein and an upper extension 4 having a perforation 5 therein. A pair of cross arms or side extensions 6 are also preferably formed on the upper portion thereof and just below the upper extension 4, so that the plate may be of the form of a cross, although this is not essential. The perforations 3 and 5 are provided for fastening members 7 which also extend through the supporting post 8 which is of such a length that it may be readily driven into the ground the proper distance to properly support the plate 1 above the ground, it being understood that the lower end of the plate extends below the bottom extension 2 of the plate 1.

A number of transverse rows of sockets 9 are formed in the main or body portion of the plate 1 and in the upper extension 4 to receive suitable letters and numerals or other characters which may be arranged on the plate 1 to give the information desired such as the relationship of the party whose grave is being marked by this head board, the name of the party, the date of the birth, the date of the death and the age at the time of the death, or any other information desired.

Each socket 9 is of the proper size to receive a block 10 preferably of rectangular form so that the letter or numeral or other character 11 on the outer or upper face of the block 10 will stand out from the front face of the plate 1 while the front or outer face of the block 10 is flush with the outer face of the plate 1. Extending through the remaining thickness of the front plate 1 from the center of each socket 9 is a shank accommodating opening 12 which has its inner end connecting with the reduced socket 9' provided for the rectangular form or squared inner end portion 13 of the shank 14 projecting from the rear face of the block 10 and adapted to be extended through the shank accommodating opening 12 to receive a nut 14 or the like upon its threaded rear or free ends so as to securely hold the char-

acter carrying block 10 in proper position within the socket 9 in the front face of the plate 1. It will be understood that the plate 1 is of suitable size and thickness and the 5 characters arranged in the order shown in Fig. 1 of the drawings, the number of sockets 9 in each transverse row being about the proper number to accommodate the words and numerals suggested by Fig. 1 of the 10 drawings and the upper transverse row consisting of three sockets to contain blocks 10 having characters spelling the usual abbreviations such as Bro., Sis., Rev., etc., while the long row immediately therebeneath will 15 accommodate a sufficient number of the blocks 10 to spell the last name and also the first name or first initials of the party for whom the head board has been provided. The number and arrangement of the sockets 20 9 may be varied as desired, and the character carrying blocks 10 with the characters 11 thereon are preferably composed of a non-rusting metal or the like so that the inscription may remain visible and intact for a 25 long period of time if not indefinitely. The plate 1 may be constructed of any suitable material such as metal and the size or construction thereof may be varied as desired.

While the preferred embodiment of the invention has been shown and described, it will be understood that many minor changes in the details of construction and arrangement of parts may be resorted to within the 30

scope of the appended claim without departing from the spirit of the invention. 35

What I claim is:—

A head board comprising the combination with a supporting post, a front plate mounted on said supporting post and provided with a plurality of transverse rows of sockets in one face, said plate having smaller auxiliary sockets inwardly of and communicating with the central portions of the first mentioned socket, said plate having shank openings extended therethrough and communicating with the second mentioned socket, character carrying blocks adapted for snug engagement in the first mentioned socket, threaded shanks for said blocks having squared portions for snug engagement 40 in the second mentioned sockets of said plate and the remainder of said shanks being adapted to be extended through the shank receiving openings of the plate, means threaded on said shank to prevent withdrawal of said blocks, said blocks having snug engagement in the first mentioned socket to prevent turning of said blocks, and characters extended outwardly from the 45 outer faces of said blocks. 50

In testimony whereof I affix my signature in presence of two witnesses.

FREDRICK R. TUCKER.
